SAMUEL S. BURT, OF MARQUETTE, MICHIGAN.

Letters Patent No. 70,799, dated November 12, 1867.

IMPROVED CAR-AXLE.

The Schedule referred to in these Letters Patent and making part of the same.

TO ALL WHOM IT MAY CONCERN:

Be it known that I, SAMUEL S. BURT, of the city and county of Marquette, and State of Michigan, have invented a new and improved Car-Axle; and I do hereby declare the following to be a full, clear, and exact description of the same, reference being had to the accompanying drawings, forming part of this specification, and in which—

Figure 1 is a side elevation of my invention.

Figure 2 is a top view of the same.

Similar letters of reference indicate corresponding parts in the two figures.

In this invention the axle-boxes are fixed to a stout iron yoke, the ends of which pass over the wheels. Each wheel runs on a short axle independently of all the others.

In order that others skilled in the art to which my invention appertains may be enabled to make and use the same, I will proceed to describe it in detail.

In the drawings, A A represent the car-wheels, running on short, stout axles B B, which bear in boxes C C attached to the stout iron yoke D, as shown. The yoke D is cast or wrought in one piece, of the form delineated in the drawings, its central portion, when in position, being nearly on a line with the axis of the pair of wheels A A, with which it is connected. Each yoke thus supports two axles and wheels, one for each side of the car. A horizontal flange or ledge, d, is formed on each end of the yoke, upon which the frame of the car is supported. The whole instrument, thus constructed, is attached to the truck, and is ready for use.

The obvious advantage of this form of axle is that it allows the wheels on opposite sides of the car to revolve independently of each other, facilitating the passage of curves, and diminishing the torsion and strain upon the axles, and consequently their liability to break. Many inventions have been devised to accomplish this object, which has long been regarded as of prime importance, but in every invention hitherto made public the bearings of the short axles have been attached to and supported by the wooden frame of the car or truck, a method of construction which has proved practically worthless, as no wooden frame is strong enough to hold the bearings with sufficient steadiness and firmness for durability and safety. It is not only necessary that the bearings of each axle should be firmly held in position with each other, but also that each pair should be as firmly held in position with the pair on the opposite side of the car, since the slightest displacement of either axle-box, by the bending or yielding of its supporting-frame, will throw the wheels out of line with each other, and thus promote the very twisting of the axles and sliding of the wheels which my invention is designed to prevent.

My yoke accomplishes the object in the cheapest and most direct manner, holding each set of axle-boxes perfectly in line with each other and with the other set, and without the possibility of getting out of line unless in case of the actual fracture of the yoke, which would never be likely to occur if it were properly made. It is easily made and conveniently handled, and requires no change in the construction of the cars upon which it is used.

Having thus described my invention, what I claim as new, and desire to secure by Letters Patent, is—

The yoke D, in combination with the axle-boxes C C, axles B B, and car-wheels A A, substantially as and for the purpose described.

SAMUEL S. BURT.
